UNITED STATES PATENT OFFICE.

CLARENCE W. CARTER, OF MINNEAPOLIS, MINNESOTA, ASSIGNOR TO CARTER-MAYHEW MANUFACTURING COMPANY, OF MINNEAPOLIS, MINNESOTA, A CORPORATION OF MINNESOTA.

DOCKAGE TESTER.

Application filed March 15, 1926. Serial No. 94,864.

This invention has for its object to provide a highly efficient device of relatively large capacity especially adapted for use as a dockage or sample tester, and, generally stated, it consists of the novel devices, combinations of devices and arrangement of parts hereinafter described and defined in the claims.

The present dockage tester involves the use of what I designate as a primary continuously acting separator and a secondary or auxiliary separator. The secondary or auxiliary separator is preferably of the character disclosed and claimed in my prior pending application Serial No. 83,548, filed of date January 25, 1926. The purposes and functions of these two separators in a combined machine will be made apparent by the following concrete illustration, assuming that the tester is to be used to separate broken from whole rice:

Dockage tests of this character are usually made from a sample consisting of one thousand grams of commingled whole and broken rice. The broken rice will frequently be as much as forty or fifty percent of the whole sample. In practice, I have found that a vibratory pocketed separating plate such as that herein employed as the secondary or auxiliary separator, the same being substantially of the structure disclosed and claimed in my above identified prior application, if made large enough, will separate the broken rice from the good rice and retain substantially every particle of the former, but that it is neither desirable nor practicable to make such plate large enough to separate and contain anywhere nearly as much as forty or fifty percent of one thousand grams. I have also found that a single rotary pocketed separating disc such as that known to the trade as the "Carter-Mayhew" separating disc, and which is disclosed and broadly claimed in my prior Patent No. 1,364,247, of date January 4, 1921, entitled "Grain separator," by its continuous or repeated rotation, can be practically used to separate by far the greater part of the broken rice from the whole rice, but that it is difficult to make such single disc separate out all that is a remaining small proportion of the broken rice from the whole rice. I have found, however, that an ideal machine of small size can be made to quickly and satisfactorily separate broken from whole

rice of a sample such as above considered. This matter will be made clear by a description of the machine illustrated in the accompanying drawings, wherein like characters indicate like parts throughout the several views.

Referring to the drawings:

Fig. 1 is a plan view of the improved machine, some parts being sectioned;

Fig. 2 is a side elevation of the machine, some parts being sectioned on the line 2—2 of Fig. 1 and some parts being broken away; and

Fig. 3 is a transverse vertical section taken approximately on the irregular line 3—3 of Fig. 2.

The numeral 4 indicates a primary hopper adapted to receive the complete sample of whole and broken rice, for example. This hopper is shown as supported in an elevated position by a framework 5 secured on a base 6. In its bottom, the hopper 4 is provided with a normally closed sliding gate 7 which, when opened, dumps the load. Working in the hopper 4 is a separating disc 8 shown as provided in both faces with pockets which, for the work at present considered, will have pockets large enough to receive only broken rice but not large enough to receive whole rice and, hence, to reject the latter. This disc is secured to an axial shaft 9 journaled in suitable bearings 10 secured on the top of the sides of the hopper 4. The shaft 9, at one end, is shown as provided with a grooved wheel or pulley 11 over which runs a belt 12 driven from another grooved pulley 13 carried by a shaft 14 of the rotor of a very small electric motor 15, the frame of which is preferably secured on the base 6. The drive illustrated reduces the speed from the motor to the separating disc, but in practice, any suitable mechanism for reducing such rotary motion to a greater extent may be employed.

To catch the broken rice carried upward by the pockets of the rotating disc, there is provided on each side thereof an inclined collecting spout 16 shown as supported from the top of the hopper by brackets 17. When the gate 7 is opened, the contents of the hopper will fall onto an inclined transfer spout 18 shown as secured to the upper end of a leg 19 which, at its lower end, is shown as pivoted to a bracket 20 on the base 6 and the forward swinging movement of which is

limited to the position shown in Fig. 2 by a stop 21 on one of the legs of the frame 5. The transfer spout 18 will direct the material into the receiving hopper of the vibratory pocketed secondary or auxiliary separating plate.

The above noted vibratory separating plate is preferably supported in a slightly inclined position, and for the purpose at present considered, is provided with pockets of a size to receive broken rice but not to receive and, hence, to reject whole rice; and this plate is mounted on a vibratory supporting bed. The supporting bed may take various forms, but, as shown, is made up of an inclined plate 22 with depending side flanges 23 secured to the upper ends of upright resilient spring metal supporting legs 24, which latter, at their lower ends, are anchored to the base 6.

The separating plate 25 is formed with closely positioned pockets 26 which, for the separation of broken from whole rice, are of such size that they will receive only the broken rice. This pocketed separating plate rests on the supporting bed 22 and, hence, will be in a slightly inclined position. Secured to and depending from the lower end of the separating plate 25 are hinge lugs 27 formed with open seats that pivotally and detachably engage a hinge rod 28 secured to and extending between the side flanges 23 of the supporting bed 22. The supporting bed 22 is shown as formed with upstanding side flanges 29 that are increased in depth at their upper ends, so that they form the sides of a receiving hopper 30 located at the upper or receiving end of the separating plate. The front plate 30^a of the hopper 30 is spaced from the separating plate so as to afford a feed passage at 31 for the even distribution of the stock over the receiving portion of said separating plate.

For vibrating the separating plate 25, and its supporting bed, any suitable means may be employed but, as shown, this is accomplished by extending the shaft 14 through a bearing 32 on the bed 6 and providing the same with a short throw crank 33 that is connected by a pitman 34 to a bracket 35 secured to one of the side flanges 23 of the supporting bed 22. The numeral 36 indicates a receptacle loosely placed on the bed 6 in position to receive material from the vibratory separating plate. The character *y* indicates the commingled whole and broken rice contained in the hopper 4.

Operation.

In the operation of the machine, the commingled stock, assumed to be whole and broken rice, is placed in the hopper 4, the gate 7, of course, being then closed. When the separating disc is then rotated, it will pick up the broken rice, carry the same

upward and discharge the same into the collecting spout 16, and by the latter will be discharged into some suitable receptacle not shown but positioned to receive the same. Under the rotation of the disc, the stock will be agitated and the greater part of the broken rice will be separated from the whole rice, which latter, being rejected by the pockets of the disc, will remain in the hopper. By this operation, the greater part of the broken rice will be removed. When there remains in the whole rice only a small percentage of broken rice, say five or ten per cent of the total amount of such broken rice, the gate 7 will be open more or less and the whole rice with a small percent of broken rice will be dropped onto the transfer spout 18 and, by the latter, delivered to the hopper 30 of the vibratory separating plate 25. As the pocketed plate 25 is vibrated, this commingled stock will be caused to slowly sift down and run over the same and the whole rice will pass over all of the pockets and into the receptacle 36, while the remaining small percentage of broken rice will be caught and retained by the pockets 26 of said separating plate. This small pocketed separating plate, as indicated, need be large enough only to catch and hold all of the remaining small portions of broken rice. When all of the whole rice has been passed over the separating plate, the separation of all of the broken rice from the whole rice will have been accomplished. Another receptacle, such as 36, should then be placed in position and the transfer spout 18, having been turned backward out of position, the separating plate can be turned upward into a vertical position, as indicated by dotted lines in Fig. 2, thereby discharging the finally collected or remaining small percent of broken rice into the overlying receptacle. The smaller portion of the broken rice thus discharged from the vibratory separating plate being then added to the broken rice taken out by the rotary disc and caught in the receptacle provided to receive the same, will assemble together all of the broken rice taken from the sample, and this, compared with the amount of whole rice delivered over the top of the vibratory separating plate, will give accurately the percentage of broken rice in respect to the whole rice.

Of course, this so-called dockage or sample tester may be used for various different purposes. When it is to be used, for example, to separate wheat from oats, or small seeds from wheat, the pockets in the separating disc and in the vibratory plate will be made of the proper size to accomplish the particular desired result. Also, from what has been said, it will be understood that the device is capable of modification within the spirit of the invention as herein disclosed and claimed.

What I claim is:

1. The combination with a primary separator having pockets adapted to receive certain objects and to reject other objects and to repeat over and over its cycles of operation, of a secondary non-repeating separator having pockets adapted to receive certain objects and reject other objects, the said secondary separator being arranged to act upon the stock from which a part thereof has been removed from said primary separator and to complete the separation thereof.

2. The combination with a separator having pockets adapted to receive certain objects and to reject other objects and to repeat over and over again its cycles of operation, of a secondary non-repeating vibratory separating plate having pockets adapted to receive certain objects and to reject other objects, the said secondary separator being arranged to act upon the stock from which a part thereof has been removed by said primary separator and to complete the separation of the two different kinds or classes of objects, said separating plate being movable into a position for discharge therefrom of the objects lodged in the pockets thereof.

3. The combination with a primary separator including a hopper and a rotary separat-

ing disc working therein, said disc having 30 pockets adapted to receive certain objects and to reject other objects, said hopper having a normally closed discharge gate, of a secondary non-repeating separator including 35 a separating plate and having pockets corresponding to those in said disc, means for rotating said disc and for vibrating said separating plate, and a transfer spout arranged to receive stock from said hopper when the gate thereof is open and to deliver 40 the same onto said vibratory pocketed separating plate, the said separating plate being movable into a position to discharge from the pockets thereof the objects lodged therein.

4. The structure defined in claim 3 in which 45 said transfer spout is movable to and from an operative position.

5. The structure defined in claim 2 in which said primary separator further includes a gathering trough adjacent the 50 upper portion of the pocketed face of said disc positioned to receive the objects lodged in the pockets thereof and carried upward thereby and discharged therefrom at the upper portion of said face. 55

In testimony whereof I affix my signature.

CLARENCE W. CARTER.
